(Cl. D44—22)

To all whom it may concern:

Be it known that I, Rudolph V. Ganz, a citizen of the United States, residing at Zanesville, in the county of Muskingum and State of Ohio, have invented a new, original, and ornamental Design for a Condiment Shaker or Similar Article, of which the following is a specification, reference being had to the accompanying drawings, forming part thereof.

ment shaker, or similar article, showing my new design,

I claim:

The ornamental design for a condiment shaker or similar article, as shown.

RUDOLPH V. GANZ.
